RICHARD A. GRAY, OF BINGHAMTON, NEW YORK

DISPLAY CARD

Substitute for application Serial No. 175,818, filed March 16, 1927. This application filed February 28, 1929. Serial No. 343,446.

My invention relates to display cards and particularly to that type applicable to use for candies, cigars, gum, etc.

The difficulty with display cards used for this purpose at present is largely that when they are unfolded to display position, no means are provided for holding them in such position and they have a tendency to fold downwardly again to a degree which makes it impossible or extremely difficult, to see, thereby destroying the display effect and function of the card.

I have provided a display card which when unfolded to display position, remains in such position indefinitely.

The principal object of my invention is to provide a display card particularly useful with candy boxes and which is frictionally held within the box or carton at one end, which end is provided with means for causing the opposite end thereof to remain in its unfolded position when raised to such position.

Specifically, I have provided a card which at its lower end or box engaging portion is wider than the upper or display portion. The wide portion is provided centrally with a slit or cutout whereby the said wider portion may be restricted to the width of the display portion, thus providing frictional means for retaining the lower end of the card within the carton, and also when so placed, producing a bow in the display portion of the card, which, due to the inherent resiliency of the card, serves to hold such display portion in its adjusted position.

Other objects and advantages in details of construction and arrangement of parts will be apparent as the description proceeds, reference now being had to the figures of the accompanying drawing wherein like reference numerals indicate like parts.

In the drawing:—

Figure 1 is a side view of a carton shown in its unopened form and provided with my

improved display card, certain parts being broken away for clearness of illustration.

Figure 2 is a plan view of my display card per se.

Figure 3 is a perspective view of a carton 50 with my display card in display position therein.

This application is substituted for application, Serial No. 175,818, filed March 16, 1927.

The reference numeral 1 indicates a box or carton adapted to contain candy or other articles of sale 2. Preferably this carton is designed as a container in which to pack and transport the articles and which can also be used as a vending carton by the purchaser, 55 from which the articles can be sold directly.

To further enhance the value of the carton as a vendor, I have provided a display card for use therewith, which as shown in Figure 1 is folded at 3 and 4 within the carton whereby to provide additional packing for the articles within the carton as well as the display card as shown in Figures 2 and 3.

The display portion 5 of the card, upon which any desired advertising matter may be 70 placed, is preferably of a uniform width, the same as that of the carton, from the fold 3 upwardly to the end thereof. From said fold 3, to the opposite end of the card, it is preferably made slightly wider than said 75 upper portion and the width of said carton. This is shown clearly by the tapered edges 6 in Figure 2.

In order that this widened end of the card may be placed within the carton in the position shown in Figures 1 and 3, and made to lie flat therein on the bottom of said carton, I have provided a split or cutout portion 7 extending from the lower end of the card upwardly to the fold 4, which latter fold is at a 85 point substantially the height of the carton. This cutout portion 7 produces the end flaps 8 at the wide end of the card, which flaps can be placed on the bottom of the carton 1 adjacent one end thereof, and due to the cutout 90

portion 7, they can be forced toward each other sufficiently to permit their assuming such position within the carton. The natural resiliency of the card tends to force the flaps 8 outwardly to their normal position, thus frictionally holding them against the side walls of the carton. The card is thus frictionally held within the carton and of course the articles 2 packed directly upon the flaps 8 also serve to maintain them in the position shown in Figure 3.

In addition to frictionally securing the card within the carton, the cutout portion serves an additional and even more important purpose. Inasmuch as the cutout portion 7 only extends upwardly to the fold 4, the inward compression of the flaps 8 permitted by said cutout portion when said flaps are positioned within the carton, produces a bow or bend shown clearly at 9 in Figure 3 in the upper or display portion of the card. The result of this is that when the display portion 5 is unfolded upwardly, and bent back beyond the end of the carton a sufficient distance to cause the bow 9 to snap to the rearward position shown in Figure 3, said display portion is held in such position because of said bow, and will not thereafter become loose and fold downwardly again as in the case with an ordinary card the same width of the carton throughout and which is folded in the same manner as my improved card is folded.

The display portion 5 of the card is therefore always maintained in its display position in full view and without danger of accidental displacement.

Of course, I do not limit myself to the specific structure shown and described as the same is capable of wide variation in form without departing from the spirit and scope of the invention. For instance, the cutout portion 7 may take the form of a straight slit and the flaps 8 thus formed caused to overlap at their inner edges when the card is placed within the carton. Also, means may be provided to permanently secure the inner edges of the cutout portion 7 in such proximity as to form a permanent bow in the display portion 5. I limit myself therefore, only by the appended claims.

1. In combination, a display card comprising a body portion, one end thereof being widened, said widened end being split centrally thereof, and a carton receiving and restricting said split widened end.

2. In combination, a display card comprising a body portion, one end thereof being widened, and said widened end being split centrally thereof, said split extending into said body portion beyond said widened end, and a carton receiving and restricting said split widened end.

3. In combination, a display card comprising a body portion, a fold laterally thereof, a carton receiving a portion of said card, said

portion having a slit on one side of said fold cooperating with said carton to produce a bow in the body portion on the opposite side of said fold.

4. In combination with a carton, a card having a display portion substantially the width of the carton and a widened end provided with a central cutout, extending inwardly from the edge thereof, whereby said end may be frictionally secured in said carton and simultaneously provide a bow in said display portion.

In testimony whereof, I affix my signature.

RICHARD A. GRAY.
